(57) **CLAIM**

The ornamental design for a combination card and key holder, as shown and described.

DESCRIPTION

FIG. 1 is a top perspective view of a combination card and key holder showing my new design;

FIG. 2 is a perspective view similar to FIG. 1 but showing the holder in its opened position;

FIG. 3 is a perspective view similar to FIG. 2 but showing the cardholders positioned over the outer closure flap;

FIG. 4 is a top plan view of FIG. 3;

FIG. 5 is a bottom plan view of FIG. 3;

FIG. 6 is a rear elevational view of FIG. 3;

FIG. 7 is a front elevational view of FIG. 3;

FIG. 8 is a left side elevational view of FIG. 3;

FIG. 9 is a right side elevational view of FIG. 3;

FIG. 10 is a top perspective view of a combination card and key holder showing a second embodiment of my new design.

FIG. 11 is a top plan view similar to FIG. 10 but showing the holder in its opened position;

FIG. 12 is a top plan view of FIG. 10;

FIG. 13 is a bottom plan view of FIG. 10;

FIG. 14 is a rear elevational view of FIG. 11;

FIG. 15 is a front elevational view of FIG. 11;

FIG. 16 is a left side elevational view of FIG. 11; and,

FIG. 17 is a right side elevational view of FIG. 11.
